UNITED STATES PATENT OFFICE.

JOHN M. SHIMER, OF WILKINSBURG, PENNSYLVANIA, ASSIGNOR TO WILSON-SNYDER MANUFACTURING COMPANY, A CORPORATION OF PENNSYLVANIA.

PUMP.

Application filed December 16, 1927. Serial No. 240,447.

This invention relates to pumps and more particularly to hot oil pumps such as are employed in petroleum refining and oil cracking plants.

5 Pumps of this type are employed for circulating oil at a temperature of 600° to 800° F., and one of the principal difficulties encountered in building a pump for use with such hot liquids has been the lack of a successful method of packing the pump plunger against the leakage of the hot liquid. At the present time, a flexible asbestos packing seems to be the best material for such use, but to insure a relatively long life of the packing, both 15 it and the plunger must be cooled to a temperature of at least 300° or 400° F.

An object of this invention is to provide a pump having an improved mechanism for cooling the pump plunger and associated 20 packing.

A further object is to provide a mechanism of the type set forth which will be simple in arrangement, rugged in construction and relatively cheap to manufacture and assemble.

25 These and other objects which will be apparent to those skilled in this particular art are accomplished by means of the invention illustrated in the accompanying drawings in which Figure 1 is a side elevation of a double 30 acting pump constructed in accordance with one embodiment of this invention. Fig. 2 is a longitudinal sectional view through the pump plunger and associated mechanism illustrated at the left in Fig. 1. Fig. 3 is a similar view 35 of the opposite plunger and Fig. 4 is a sectional view similar to Fig. 2 illustrating a different way of carrying out the present invention.

As illustrated, the present invention is 40 shown in connection with a double acting pump 5 having opposed cylinder bores, 6 and 7, provided with reciprocating plungers 8 and 9, respectively, which are simultaneously operated from any desired source of power such, 45 for example, as a steam cylinder 10 having a piston rod 11 connected to the cross head 12 of the adjacent pump plunger 8, the cross head being supported upon a cradle 13 slidably mounted on the usual rods 14. The opposite 50 plunger 9 is reciprocated through the medium of a cross head 15 supported on a cross head slide 16 and connected to the cross head 12 of the first plunger by tie rods 17 for simultaneous operation of the respective plungers. Each plunger is provided with a pack-

ing 18 of any desired type for preventing leakage of oil along the plunger surface, and mechanism is employed for maintaining the plunger and packing at a temperature sufficiently low to provide for relatively long life 60 of the packing.

In the present instance, this cooling is attained by flushing a cooling medium through the interior of the hollow plungers. A spider 19 or similar support is mounted upon the 65 cradle supporting rods 14 between the steam cylinder 10 and the adjacent cross head 12, the spider having a hub 20 provided with an opening 21 through which the associated piston rod extends. A liquid supply conduit for delivering a cooling medium into the interior of the plunger 8 is formed by a hollow rod or pipe 22 which is threaded into the hub of the spider so as to communicate directly with inlet 70 passages 23 formed therein. The liquid sup, 75 plied conduit extends through the cross head 12 and the sliding or telescoping joint between the conduit and the cross head is closed by a packing 24. The conduit is of such length as to deliver a cooling medium as closely adjacent 80 the inner end of the associated plunger 8 as is possible. An outlet pipe or conduit 25 is threaded into the hub 20 so as to communicate directly with an outlet 26 formed therein and the outlet conduit has a sliding or telescoping 85 connection with the cross head 12 which is sealed by a packing 27. The outlet conduit is substantially shorter than the inlet conduit so as to withdraw the cooling medium from the outer end of the hollow plunger, opposite to 90 the end at which it is supplied. It will, of course, be understood that the proper outside connections for conveying the cooling medium to and from the inlet and outlet conduits are associated with the inlet and outlet passages 23 and 26, respectively, in the spider hub 20. It is apparent that the sliding connections between the cross-head 12 and the fluid-conveying conduits 22 and 25 provide, in effect, flexible fluid-conveying connections 100 between the passages 23 and 26 and the interior of the hollow plunger.

The opposite plunger 9 is cooled in the same manner. A bracket 28 is mounted at the rear of the associated cross head 15 and an inlet pipe or supply conduit 29 is connected thereto in direct communication with an inlet port 30, the conduit 29 extending through the cross head 15 and into the hollow plunger 9 a sufficient distance to deliver the cooling 110

fluid thereto at its inner or hottest end, the flexible connection in the form of a sliding or telescoping connection or joint between the cross head and inlet conduit being packed by 5 a suitable packing 30. The outlet pipe 31 is connected to the supporting bracket 29 so as to communicate directly with an outlet port 32 formed therein, the outlet conduit being of such length as to withdraw the cooling 10 fluid from the outer or cooler end of the associated plunger. Like the inlet conduit, the outlet conduit 31 extends through the cross head 15 and the slideable joint is packed by suitable packing 33.

15 It will be readily apparent to those skilled in this particular art that, in the case of a pump under a certain size, the pump plungers and cross heads will be too small to permit the liquid conduits extending through the latter. In this case, the liquid may be flushed 20 through the plunger by means of connections associated with the lateral faces of the cross head, instead of connections extending straight through. As illustrated in Fig. 4, 25 the relatively small plunger 35 is reciprocated by a cross head 36 mounted upon a slide or support 37. The inlet pipe 38 is connected directly to the cross head so as to communicate with an inlet passage 39 formed by a bore 30 extending laterally outward to the outer face of the cross head. The outer end of the bore is closed by a plug 40 or the like and an additional passage 41 extends at right angles to the passage 39 adjacent the outer edge of the 35 cross head. A conduit formed by telescoping rods 42 and 43 connects the passage 41 with an inlet connection formed by a flanged member 44 having a passage 45 communicating with the pipe 43 at one end and forming 40 an inlet port 45' at the other. The member 44 is removably mounted on the pump frame 45. An outlet passage 47 is formed in the cross head by a laterally extending bore closed 46 at its outer end by a plug 48. A second bore 49 communicates directly with the outlet bore 47 and is connected to an outlet conduit 50 formed by telescoping rods 50 and 51 leading to an outlet connection 52, similar in all respects to the inlet connection 44, and providing 55 an outlet port 52'. The telescoping joints between the rods 42 and 43 and the rods 50 and 51 are packed with the usual packings 53 of any desired form. It will be observed that these telescoping joints provide a flexible fluid-conveying conduit between each of the inlet and outlet connections and the interior of the plunger.

Referring to Figs. 1 to 3, the inlet 23 is connected to any desired source of cooling fluid such, for example, as water, and the outlet 26 in the spider hub 20 is connected to any suitable discharge. The water or other cooling medium is carried by the inlet conduit 22 to the inner or hottest end of the plunger 8 and flows backwardly through the plunger

to the outlet conduit 25 and outlet 26. The constant flushing of the cooling medium through the plunger maintains it and the associated packing 18 at such a temperature that the life of the latter is materially prolonged. A much shorter plunger stuffing box can be employed than is the case when outside cooling is relied upon, and there is no inward leakage of a cooling medium into the pump, as is intentionally arranged for in some 70 of the stuffing boxes employing outside cooling. The result is that water, the most efficient cooling medium, can be used and the full benefit of direct contact between the cooling medium and the plunger is obtained, this latter, of course, not being possible in exterior cooling of the plunger by water. The operation 75 of the opposite plunger 9 is similar.

Referring to Fig. 4, the inlet port 45' formed in the nozzle or member 44, is connected to a source of supply and the outlet port 52' in the member 52, is connected to a suitable discharge. The cooling medium flows through the inlet member 44, the telescoping pipes 42 and 43, the cross passage 39 in the cross head to the inlet conduit 38. It is flushed through the plunger and flows out through the discharge outlets 47 and 49 formed in the cross head, through the telescoping outlet pipes 50 and 51 and through the outlet member 52 to the discharge. It will be apparent that the same advantages are inherent in this construction as are obtained in the other modifications described.

Although I have set forth certain specific 100 constructions of this invention, it will be apparent that various changes, additions, substitutions and omissions can be made in the specific details thereof without departing from the spirit of this invention or the scope 105 of the appended claims.

What I claim as new and desire to secure by Letters Patent is:

1. The combination in a hot oil pump of a 110 reciprocating hollow plunger, a cross head associated therewith, means for delivering a cooling medium to the interior of said plunger through said cross head and means for removing said medium from said plunger through said cross head.

2. The combination in a hot oil pump of a 115 hollow plunger, a reciprocating cross head for operating said plunger, a cradle for supporting said cross head, means including passages in said cross head for flushing a cooling medium through the interior of said plunger, an inlet associated with one of said passages for delivering a cooling medium thereto, an outlet for another of said passages, means for securing said inlet and outlet to the pump frame, and telescoping connections between said cross head and said inlet and outlet.

3. The combination in a hot oil pump of a 120 hollow plunger, a reciprocating cross head

- for operating said plunger, liquid conveying ducts formed in said cross head for permitting a cooling medium to be flushed through said plunger, a member provided with an 5 inlet port mounted on the frame of said pump, a second member provided with an outlet port mounted on said frame, and telescoping conduits connecting said members with the ducts in said cross head.
- 10 4. The combination in a hot oil pump of a hollow plunger, a reciprocating cross head for operating said plunger and provided with fluid passages communicating with the interior of said plunger, removable inlet and outlet 15 connections mounted on the pump frame and telescoping conduits connecting the passages in said cross head with said members.
5. The combination in a pump of a movable head, a hollow plunger associated therewith so as to be operated thereby and means 20 for circulating a cooling medium through the interior of said plunger including means for conveying a cooling medium through said head to the end of said plunger remote from 25 said head and means for removing said cooling fluid through said head from the portion of said plunger adjacent said head.
6. The combination in a pump of a hollow plunger, means for reciprocating said plunger and means for circulating a cooling fluid 30 through the interior of said plunger including stationary inlet and outlet connections and flexible fluid conveying conduits between said connections and the interior of said plunger. 35
7. The combination in a pump of a hollow plunger, a reciprocating cross head associated therewith, liquid conveying passages formed in said cross head for permitting a cooling medium to be flushed through said plunger, a stationary inlet member, a stationary outlet member and flexible conduits connecting said members with the passages in said cross head. 40
8. The combination in a pump of a reciprocating cross head, a hollow plunger rigidly connected thereto and movable therewith and stationary fluid conveying conduits provided with telescoping connections with said cross head for passing a cooling fluid through the 45 interior of said plunger. 50

In testimony whereof, I have hereunto subscribed my name this 13th day of December, 1927.

JOHN M. SHIMER.
